ELECTRIC IRON HANDLE

Robert O. Ernest, Oak Park, Ill., assignor to Sunbeam Corporation, Chicago, Ill.

Filed Jan. 17, 1972, Ser. No. 218,645

Term of patent 14 years

Int. Cl. D7—05

U.S. Cl. D7—204

FIG. 1 is a perspective view of an electric iron handle embodying my new design;

FIG. 2 is an enlarged top plan view thereof;

FIG. 3 is a side elevational view thereof opposite that shown in FIG. 1;

FIG. 4 is a front elevational view thereof; and

FIG. 5 is a rear elevational view thereof.

I claim:

The ornamental design for an electric iron handle, as shown.
